UNITED STATES PATENT OFFICE.

FELIX GOTTSCHALK, OF STIRLING, NEW JERSEY.

AUTOMATIC FIRE-ALARM SYSTEM.

1,147,014.

Specification of Letters Patent. Patented July 20, 1915.

Original application filed February 13, 1914, Serial No. 818,503. Divided and this application filed September 19, 1914. Serial No. 862,482.

To all whom it may concern:

Be it known that I, FELIX GOTTSCHALK, a citizen of the United States, residing at Stirling, in the county of Morris and State 5 of New Jersey, have invented certain new and useful Improvements in Automatic Fire-Alarm Systems, of which the following is a specification, reference being had to the accompanying drawing.

10 My invention relates to fire alarm systems, and has for its principal object the utilization of the ordinary telephone instrument and its associated line and central office equipment, for the transmission of a characteristic 15 alarm signal by the mechanical operation of the telephone receiver hook by means of a suitable device, said device being released to operate by means of a fusible link or thermostatic device.

20 A further object is the elimination of any electrical connections to the telephone instrument or its circuit, the sending of a characteristic fire signal being accomplished entirely by the mechanical actuation of the 25 telephone receiver hook.

Another object is to produce a mechanical attachment easily installed on any type of telephone instrument, for the purpose specified.

30 There are other objects as hereinafter set forth.

In my pending application, Serial No. 818,503, of which this is a division, I disclose and claim a receiver hook held in its 35 normal or restrained position by means of a fusible link, so that when the link is melted by an abnormal rise in temperature, the hook switch will be released, thereby signaling the central office. It is obvious, however, 40 that with the foregoing arrangement, the signal is not characteristic, that is, the effect at the central office would be the same if the telephone receiver were accidentally removed from the hook, or if the line became crossed or if any other accident should occur that would cause a permanent signal to be displayed.

To obviate the above, my present invention contemplates means whereby a distinctive signal is given in the exchange in case of fire.

The accompanying drawing is a view of a complete apparatus adapted to give the characteristic signal in case of fire.

55 For the sake of illustration, a desk tele-

phone instrument is shown, but it is obvious that the hook actuating mechanism may be clamped on a wall set or in fact on any type of telephone instrument equipped with a receiver hook or any other type of switching mechanism.

1 denotes the frame work of the telephone instrument. 2, the usual receiver hook, its normal or restrained position being shown in heavy lines and its operated position, in 65 dotted lines. Attached to the hook switch 2 in any suitable manner is the lever 3 projecting from the actuating mechanism 4, which may be any suitable form of clock work adapted to be wound by the key 5.

6 is a fusible link adapted to melt at an abnormal temperature—say 150 degrees Fah. This is clamped between a fixed support 7 and a movable support or pawl 8. When 6 melts due to abnormal heat, the pawl 8 is 75 released, the clock work is set in motion, member 3 is actuated and hook switch 2 is alternately raised and lowered as long as the clock work is running. This movement of the hook switch may readily be made dis-

70 tinctive in character by means of the escapement of the clock work in a manner well known to those versed in the art, so as to repeat the Morse character "F" or to spell in Morse characters "Fire" or to give any 85 other desired signal; the hook switch of the telephone being operated similar to a telegraph key and thereby operating the central office signal like a telegraph relay, or if the exchange operator listens in, affecting the 90 head receiver in a distinctive manner.

It will be seen that my invention consists of utilizing the standard telephone instrument, line and central office apparatus for the purpose of transmitting a distinctive 95 fire signal without complicating same by the addition of electrically operated devices for sending in the alarm, and that my device is purely mechanical and does not affect the transmission of the telephone line in any 100 manner and that by disconnecting the member 3, the instrument may be used as an ordinary telephone.

Having thus described my invention, I claim:

1. In an alarm system of the character described, a telephone instrument having switching mechanism, means connected to said mechanism for moving same to its "on" and "off" positions, and means adapted to 110

be operated by heat for starting said actuating means.

2. In an alarm system of the character described, the combination with a circuit 5 leading from a premises to be protected, to a telephone exchange, a signal and a source of energy, of a telephone instrument having switching mechanism, and thermostatically controlled means for moving said switching 10 mechanism to its "on" and "off" positions, thereby producing a characteristic signal in said exchange.

3. In an alarm system of the character described, a telephone instrument having 15 switching mechanism, spring driven actuating means for moving said switching mechanism to its "on" and "off" positions and a fusible link restraining said actuating means in a non-operative position, said link 20 adapted to melt in the presence of abnormal heat.

4. In an alarm system of the character described, a telephone instrument having a switch hook, a self-contained mechanical 25 actuating device clamped to said switch hook for moving the same to its "on" and "off" positions, mechanical means holding said actuating means and a fusible link connected to said holding means and adapted to 30 melt in the presence of abnormal heat.

5. In an alarm system of the character described, a telephone instrument having switching mechanism, a mechanical actuating device connected to said switching mechanism and adapted to operate same in a pre- 35

determined manner, restraining means connected to said actuating means and a fusible link holding said restraining means and adapted to melt in the presence of abnormal heat, and thereby cause the operation of said 40 actuating means, substantially as described.

6. In an alarm system of the character described, a telephone instrument having a switch hook, mechanical actuating means for said switch hook adapted to raise and lower 45 same in a predetermined manner, means comprising a suitable clamp for connecting said actuating means to said switch hook, and means comprising a fusible link for holding said actuating means in its non-operative position, said fusible link being 50 adapted to melt in the presence of abnormal heat, thereby releasing said actuating means and causing the operation of said switch hook. 55

7. An attachment for telephone instruments, comprising in combination, a spring actuated device having a member adapted to engage the switch hook of said telephone and a fusible link, both ends of which are 60 attached to said spring actuated device for restraining same except in the presence of abnormal heat.

In testimony whereof I hereunto affix my signature in the presence of two witnesses. 65

FELIX GOTTSCHALK.
